US0D1051139S

(12) **United States Design Patent** (10) Patent No.: **US D1,051,139 S**
(45) Date of Patent: ** Nov. 12, 2024

(54) **DISPLAY SCREEN WITH GRAPHICAL USER INTERFACE**

(71) Applicant: **Meta Platforms, Inc.**, Menlo Park, CA (US)

(72) Inventors: **Xue Ding**, Los Altos, CA (US); **Nathan Andrew Sharp**, San Francisco, CA (US)

(73) Assignee: **Meta Platforms, Inc.**, Menlo Park, CA (US)

(**) Term: **15 Years**

(21) Appl. No.: **29/771,120**

(22) Filed: **Feb. 19, 2021**

Related U.S. Application Data

(63) Continuation of application No. 29/689,398, filed on Apr. 29, 2019, now Pat. No. Des. 914,031.

(57) **CLAIM**

The ornamental design for a display screen with graphical user interface, as shown and described.

DESCRIPTION

The FIGURE is a front view of a display screen with graphical user interface showing the claimed design. The broken lines showing a display screen and elements of the graphical user interface illustrate portions of the article, and form no part of the claimed design.

1 Claim, 1 Drawing Sheet
